UNITED STATES PATENT OFFICE.

HARVEY M. WOOD, OF LOS ANGELES, CALIFORNIA.

SAW-CLAMP.

1,137,301.

Specification of Letters Patent. Patented Apr. 27, 1915.

Application filed September 16, 1912. Serial No. 720,669.

To all whom it may concern:

Be it known that I, HARVEY M. Wood, a citizen of the United States, residing at Los Angeles, in the county of Los Angeles and State of California, have invented a new and useful Saw-Clamp, of which the following is a specification.

The object of this invention is to provide a cheap, simple, easily manufactured, assembled and operated saw clamp adapted for clamping the saw to hold it during the operation of setting and joining and to also hold the saw during the operation of filing.

A further object of the invention is to provide a saw clamp construction which can be largely manufactured from stamped sheet metal.

The accompanying drawings illustrate the invention.

20 Figure 1 is a perspective view of the saw clamp fastened to a bench, a fragment of which is shown. Fig. 2 is a plan view of the saw clamp detached. Fig. 3 is a longitudinal section on line x^3 , Fig. 2, turned end 25 for end and looking in the direction of the arrow. Fig. 4 is an enlarged cross section of Fig. 1 on line indicated at x^4 , Figs. 2 and 3, a fragment of a saw being shown clamped for setting and joining. Fig. 5 is a cross section 30 of a stamping to form the base. Fig. 6 is a cross section of a stamping for the double slidable jaw. Fig. 7 is a cross section of a stamping for the double acting jaw-clamping slide. Fig. 8 is an elevational section on line indicated at x^8 , Figs. 2 and 3, of a stamping for one of the end arms. Figs. 35 9, 10, 11 and 12 are views of the blanks from which the four stampings shown in Figs. 5, 6, 7 and 8 are formed. Dotted lines indicate 40 the points at which the bending takes place. Figs. 2, 3, 5, 6, 7, 8 and 12 are on a scale twice that of Figs. 9, 10 and 11. Fig. 1 is on a larger scale and Fig. 4 on a still larger scale. Fig. 13 is an inverted plan of the 45 pivot post and bearing block therefor.

The base is an oblong rectangular piece of sheet metal bent to form the dependent bench flange 1, the horizontal bed 2 and the upright clamp flange 3. The bed is perforated with end rivet holes 4, a central rivet hole 5 and end fastening holes 6. The dependent bench flange 1 is provided with spurs 7 struck up from the flange and projecting underneath the bed 2 to insert into 50 the bench 9.

The end arms are formed with a straight limb 10 and an overhanging arch 11; the straight limbs 10 being provided with rivet holes 12 and a fastener hole 13 corresponding to the holes 4 and 6 in the bed and said limbs 10 being fixed to the bed by rivets 14. The overhanging arches 11 are provided in their lower free ends with holes 15 for fasteners which may be in the form of rivets 16 by means of which the front clamp bar 17 is 60 fastened to the inner faces of the free ends of the overhanging arches. The front clamp bar 17 is preferably of metal in the form of channel iron and is rigid so as to form a firm support for the saw to resist the forward thrust of the saw when clamped.

The sliding clamp member is a sheet metal channel stamping having a web 18, an upright clamp flange 19 and an upright clamp bar holding flange 20; the web 18 being provided with a transverse slot 21 to register with the central perforation 5 and the clamp bar holding flange 20 being provided with end perforations 22 to receive fasteners as the screws 23 which are screwed into the 70 wooden rear clamp bar 24 which may be a rectangular bar of wood corresponding in length with the sliding clamp member to co-operate with the metal bar 17 for clamping the saw when it is to be filed. The clamp 75 flange 19 of the sliding clamp is designed to co-operate with the upright flange 3 to clamp the back of the saw and hold it during the operation of setting and jointing.

The clamp post 25 is provided at its lower 90 end with a reduced pin 26 to fit the perforation 5 in the bed 2, and is provided at the other end with a head 27, and is inserted through the bearing block 28 which is provided with a flange 29 to rest on the slide 95 30 and is also provided with an oblong boss 31 that fits the diagonal slot 32 in said slide 30 which is an oblong piece of sheet metal having upturned ends 33 that form handles by which the slide 30 can be moved endwise 100 in the channel of the sliding clamp. The slide 30 is provided intermediate its ends with the diagonal slot 32 in which the boss 31 fits so that when the slide is moved endwise it reacts upon the boss and the fixed 105 clamp post, so as to be shifted laterally simultaneously and correspondingly with the endwise shifting movement; and by engagement with the flange 19 or 20 as the case may be, will shift the clamp plate 18 in one 110

or the other direction to close the rear clamp slot 34 or the front clamp slot 35 as the case may be.

To assemble the clamp the end arms 10, 5 11 are first riveted to the angle iron front clamp bar 17 by rivets 16 and then said end arms are riveted to the bed 2 by rivets 14. Then the wooden rear clamp bar 24 is fastened to the flange 20 of the sliding clamp member by the screws 23; the slide 30 is then put in place on the web 18 between the flanges 19, 20; the boss 31 of the bearing block 28 is inserted into the slot 32 with the flanges 29 resting on the slide 30; and when 10 15 the clamp post 25 is inserted through the bearing block, the slot 21, and the hole 5 and is there secured by suitable means as by riveting the pin 26 to the bed 2.

To install the clamp on a work bench 9, 20 the bed 2 is placed on the top of the bench and the heads of the rivets 14 support the bed above the bench 9 to accommodate the end pin 26. The workman then taps the dependent flange 1 to drive the spurs 7 into 25 the bench. Then fasteners in the form of screws or nails 36 are driven through the holes 13 into the bench thus firmly fixing the clamp in place. The clamp is then ready for use.

30 To clamp the saw for filing, its toothed edge will be inserted up through the slot 35 to bring the teeth above the bars 17 and 24. And the slide 30 will then be driven to the left in Figs. 1, 2 and 3 thus moving the bar 24 to the left in Fig. 4. A reverse operation opens the saw setting clamps and releases the saw. The wooden clamp bar 24 is wider than the metal clamp bar 17 and its top is above the level of the top of the bar 17 so as to give a strong backing behind the saw just below the saw teeth and to give ample room in front in which to handle the file.

45 To clamp the saw 37 for setting it, the back of the saw is inserted with its back in the slot 34 and resting on the ends of the arms 10 and the slide 30 is then driven to the right in Figs. 1, 2 and 3, thus shifting the sliding clamp member to clamp the saw in slot 34. A reverse operation releases the saw.

50 The tops of the arms 10 support the back of the saw above the bend between the web and flange of the bed 2 so that the flat face of flange 3 may fit tightly against the saw to hold it firmly.

55 When the saw clamp is fixed to a bench it is not obtrusive on account of its compact construction, and the sliding clamp member 60 may be shifted in one and the other direction to operate the front and rear clamps alternatively.

I claim:

65 1. A saw clamp comprising forward clamping means adapted to hold the saw

while being filed, rearward clamping means adapted to hold the saw while the teeth are being set, and means located between said forward and rearward clamping means for operating the clamps alternatively.

2. In a saw clamp, a relatively fixed clamp member having two saw engaging portions, a relatively movable clamp member coöperating with the said saw engaging portions to hold a saw in a position for filing and in a position for teeth setting, and sliding means for shifting the movable clamp member, alternatively into coöperative clamping positions with the said saw engaging portions, the said sliding means having a longitudinal movement relative to the movable clamp member, and a corresponding longitudinal and lateral movement relative to the fixed clamp member, to adjust to the coöperative clamping positions.

3. A saw clamp comprising clamping means having two elongated clamping bars, the upper face of one being at a higher level than the upper face of the other, said clamping means being adapted to hold the saw while being filed, other clamping means adapted to hold the saw while the teeth are being set, and means located between the two said clamping means for operating the clamps alternatively.

4. A saw clamp comprising a base carrying two clamping bars, each of which bars form part of two separate clamping means, a member movably mounted on said base, said member also carrying two clamping bars, each of which last said bars also form a part of the two said separate clamping means, and means for moving said member for operating the two said clamping means alternatively.

5. A saw clamp comprising a base, two clamping bars thereon, each of which bars forms a part of separate clamping means, a laterally adjustable plate mounted on said base, clamping bars on the adjustable plate complementary to the first-named bars, and means for alternatively adjusting the separate clamping means to an operative position consisting of an operating plate sliding longitudinally upon the laterally adjustable clamp plate having a diagonal slot, and a retaining member projecting from the base into said slot in the operating plate causing the operating plate to have simultaneous corresponding longitudinal and transverse movements in effecting the adjustment of the clamping means.

6. A saw clamp comprising a base provided with two separate clamping bars, a post on said base, a clamp plate slidably mounted on said base and provided with two separate clamping bars adapted to co-operate with the first said clamping bars so as to form two separate saw-clamping means, and an operating plate located between the

- clamping bars of said clamp-plate, said operating plate having a diagonal slot adapted to coöperate with said post so as to operate the two saw-clamping means alternatively.
5. 7. A saw clamp comprising a sheet metal base provided with a forward and a rearward clamping bar, a post mounted on said base, a sheet metal clamp-plate slidably mounted upon said base and also provided with a forward and a rearward clamping bar, and a plate located between the two last said clamping bars and having a diagonal slot in which said post extends; the last said plate being adapted to move the clamp-plate forward and rearward alternatively.
10. 8. A saw clamp comprising fixed clamping bars, a post between said bars, a channel member having flanges and slidably mounted between the fixed clamping bars, the flanges of said channel member coöoperating with the fixed clamping bars to form two complete saw-clamping means, a plate between said channel flanges and slidably mounted between the same, the said plate having a slot adapted to coöperate with said post, so that said plate may operate either of said saw-clamping means alternatively.
15. 9. A saw clamp comprising fixed clamping bars, a fixed post between the same, a
- channel member slidably mounted between the fixed clamping bars the flanges of said channel member coöoperating with the fixed clamping bars to form two complete clamps, a plate fitting between the channel flanges and slidably mounted between the same, the plate having a diagonal slot through which the post extends, and means attached to said plate for conveniently sliding the plate longitudinally of the channel.
10. In a saw clamp, the combination with a base and a relatively adjustable clamp bar plate mounted thereon, of complementary clamping bars on the base and adjustable plate co-acting to hold a saw in two positions, and actuating means relative to the base and adjustable plate having simultaneous and corresponding lateral and endwise movements effectual in adjusting, setting, and releasing the complementary clamping bars.
40. 45. 50. In testimony whereof, I have hereunto set my hand at Los Angeles, California, this 9th day of September, 1912.

HARVEY M. WOOD.
